(57) **CLAIM**

We claim the ornamental design for a side handle, as shown and described.

DESCRIPTION

FIG. 1 is a perspective view of the side handle, showing our new, original and ornamental design;

FIG. 2 is a side view thereof;

FIG. 3 is a top view thereof;

FIG. 4 is a bottom view thereof;

FIG. 5 is a front view thereof; and,

FIG. 6 is a back view thereof.

The broken lines showing portions of the article form no part of the claimed design.
